UNITED STATES PATENT OFFICE

162,714

BOUDOIR CAP

Arlene Carol Dahl, Beverly Hills, Calif.

Application December 30, 1949, Serial No. 6,921

Term of patent 14 years

(Cl. D3—13)

To all whom it may concern:

Be it known that I, Arlene Carol Dahl, a citizen of the United States of America, residing in Beverly Hills, in the county of Los Angeles, State of California, have invented a new, original, and ornamental Design for a Boudoir Cap, of which the following is a specification, reference being had to the accompanying drawing, forming part hereof.

Fig. 1 is a front perspective view of a boudoir cap showing my new design; and

Fig. 2 is a rear perspective view thereof.

The side of the cap not shown in the drawing is identical in appearance with the side shown.

I claim:

The ornamental design for a boudoir cap, as shown and described.

ARLENE CAROL DAHL.
